United States Patent Office

Des. 206,870
Patented Feb. 7, 1967

206,870

BUILDING

Norman T. Gilroy, 5 Taylor Lane,
Larkspur, Calif. 94913

Filed Mar. 29, 1965, Ser. No. 84,490

Term of patent 14 years

(Cl. D13—1)

FIG. 3

FIG. 4

FIG. 1 is a right side view in elevation of my building design, which is the same as the left side elevational view; FIG. 2 is a view in front elevation;

FIG. 3 is a view in rear elevation; and FIG. 4 is a top plan view.

The dominant features of the design reside in the full lines in the drawing. The dotted lines showing the platform and supports are shown for illustrative purposes only.

I claim:

The ornamental design for a building, substantially as shown and described,
